JOHN TIERNAN AND FREDERICK JOHN LEIBROCK, OF JERSEY CITY, NEW JERSEY

CLIP APPLYING TOOL

Application filed April 21, 1931. Serial No. 531,758.

This invention relates to a tool for applying hairpin clips to angle carrying bars, as used in building constructions.

In building constructions, it is common practice to support furring irons by angle carrying bars, which, in turn, are supported by toggle hangers which depend from the floor construction. The angle carrying bars are attached to the toggle hangers by rivets or the like, and are for the purpose of carrying the furring irons which extend in angular relation to the angle carrying bars, and relatively close together. This arrangement leaves a space between the furring irons and the lower surface of the floor. It has been the practice to secure the furring irons to the angle carrying bars by hairpin clips which include bight portions adapted to embrace the furring irons, and leg portions adapted to be bent over the upper edges of the angle carrying bars.

The application of these hairpin clips has been somewhat difficult in the past, and it has been common practice to first slip a hairpin clip over the furring iron after the latter has been put in place against the lower sides of the angle carrying bars, so that the bent ends or legs of the hairpin clip overlie the upper edge of the angle carrying bar. To bend these extended ends or legs downwardly to embrace the angle carrying bar and to form, in effect, hooks over the upper edge of the same, a practice has been resorted to which includes the placing of a small pipe over these ends or legs and bending them down as far as possible with the use of this pipe. To get the maximum action of this pipe, it has been customary to bend the pipe at an angle so that it will contact with the furring irons or with the angle carrying bar only after the legs of the hairpin clip have been bent to a considerable extent. However, it has not been possible to bend these legs by means of this pipe into their final position, and the practice has been, after removal of the pipe, to complete the bending by striking the legs with a hammer.

The above practice has been attended by many disadvantages. The relatively small space between the floor and the furring irons

affords an inconvenient working space, and the result has been that the hammering down of the legs not only consumes a comparatively great amount of time, but does not insure the clinching of the hairpin clip on the angle carrying bar in such position that the furring irons will be held tightly and immovably against the angle carrying bars. There are many other disadvantages incident to the use of the bending pipe and hammer.

The primary object of the present invention, therefore, is to provide a tool for applying the hairpin clips in such manner that all of the above referred to disadvantages are overcome.

A more specific object of the present invention is to provide a relatively light and simple form of tool which may be readily handled and manipulated, and by means of which the application of the hairpin clips will be greatly facilitated.

The present invention consists in the novel form, combination and arrangement of parts hereinafter more fully described, shown in the accompanying drawings and claimed.

In the drawings:

Figure 1 is a view, partly in side elevation and partly broken away and in section, showing a tool embodying the present invention as it appears when in use preparatory to clinching a hairpin clip on an angle carrying bar.

Figure 2 is a sectional view taken on line 2-2 of Figure 1.

Figure 3 is a fragmentary elevation showing the upper portion of the tool as it appears looking toward the left of Figure 1.

Figure 4 is a fragmentary horizontal section on line 4-4 of Figure 1.

Figure 5 is a perspective view of one of the hairpin clips as it appears before being clinched; and

Figure 6 is a similar view of the clip as it appears after being clinched.

In the commercial art, a hairpin clip such as shown in Figure 5, is commonly used. This clip includes a bight portion 5 which is adapted to engage the furring iron, and legs 6 which are adapted to be snapped over the upper edge of the carrying bar 7 which is sup-

ported by the usual toggle hangers depending from the floor of the building. At the juncture between the legs 6 and the bight portion 5 of the hairpin clip, the wire is bent to form seats 8 which are adapted to engage over the upper edge of the carrying bar 7.

The present invention embodies an improved tool by means of which the legs 6 of the clip may be clinched into position or bent down against the inner face of the vertical flange of the carrying bar 7 as indicated by dotted lines in Figure 1, whereupon the clip will appear as shown in Figure 6. As shown, the present tool is of the plier type and embodies a pair of handles 9 and 10, the outer end of the handle 9 being extended laterally and slotted as at 11, and the outer end of the handle 10 being pivoted to the handle 9 within the slot 11 as at 12. Formed integral with the outer end of the handle 9 is an angular inner jaw comprising an inwardly extending portion 13 and a laterally extending free end portion 14, adapted to respectively flatly engage the outer faces of the vertical and horizontal flanges of the angle carrying bar 7 as shown in Figure 1. The outer face of the jaw portion 13 is provided with a central longitudinal rib 15, and the free end portion 14 of the inner jaw is narrower than the portion 13 and of a width similar to the width of the rib 15. The clip is thus adapted to be sprung onto and to frictionally engage the inner jaw of the tool to be carried by the latter, the bight portion 5 of the clip embracing the jaw portion 14 and engaging opposite sides of the rib 15 of the jaw portion 13 as shown clearly in Figures 1, 3 and 4. In this way, the clip may be applied to the tool, and then the tool may be positioned to properly set the clip in place relative to the carrying bar 7 so that it may be readily clinched without one hand of the operator being used to position and hold the clip in place.

The tool further embodies a lateral extension or end portion 16 on the outer end of the handle 10 having a transverse plate-like outer jaw 17 formed integral with the free end thereof. The outer jaw 17 is arranged to project inwardly so that its inner transverse edge will contact with and extend across the legs 6 intermediate the ends of the latter and a distance laterally of the vertical flange of the carrying bar 7 as shown in Figure 1. It will be further noted that when the jaws are separated, the handles 9 and 10 will also be separated, so that upon pressing the handles together the outer jaw 17 is brought downwardly and inwardly so as to effectively clinch the legs 6 against the inner face of the vertical flange of the carrying bar 7 as indicated by dotted lines in Figure 1. Due to engagement of the outer jaw 17 with the intermediate portions of the legs 6, the clip will be effectively clinched so that they need

not be finally forced down by hammering or the like.

After the clip has been applied, the jaws may be separated and the jaw portion 14 readily withdrawn from the bight portion 7 of the clip.

While we have described a particular embodiment of our invention, it is to be understood that minor changes may be made within the spirit and scope of the invention as claimed.

What we claim as new is:

1. A tool for applying hairpin clips to angle carrying bars including a pair of handles pivoted together, an angular inner jaw integral with one of said handles and embodying an inwardly extending portion and a laterally extending free end portion adapted to respectively flatly engage the outer faces of the flanges of the carrying bar, and a transverse plate-like outer jaw integral with the other handle and arranged to engage and extend across the intermediate portions of the legs of a hairpin clip when the latter is disposed with its bight portion embracing the free end portion of the inner jaw.

2. A tool for applying hairpin clips to angle carrying bars including a pair of handles pivoted together, an angular inner jaw integral with one of said handles and embodying an inwardly extending portion and a laterally extending free end portion adapted to respectively flatly engage the outer faces of the flanges of the carrying bar, and a transverse plate-like outer jaw integral with the other handle and arranged to engage and extend across the intermediate portions of the legs of a hairpin clip when the latter is disposed with its bight portion embracing the free end portion of the inner jaw, said inwardly extending portion of the inner jaw having a central longitudinal rib adapted to be engaged at opposite sides by the bight portion of the clip, whereby the clip may be held by the tool substantially against the carrying bar.

3. A tool for applying hairpin clips to angle carrying bars including a pair of handles pivoted together, an angular inner jaw integral with one of said handles and embodying an inwardly extending portion and a laterally extending free end portion adapted to respectively flatly engage the outer faces of the flanges of the carrying bar, and a transverse plate-like outer jaw integral with the other handle and arranged to engage and extend across the intermediate portions of the legs of a hairpin clip when the latter is disposed with its bight portion embracing the free end portion of the inner jaw, said inwardly extending portion of the inner jaw having a central longitudinal rib adapted to be engaged at opposite sides by the bight portion

of the clip, whereby the clip may be held by the tool substantially against the carrying bar, the free end portion and rib of the inner jaw being of a width to require springing of the clip thereon.

5 In testimony whereof we affix our signatures.

JOHN TIERNAN.

FREDERICK JOHN LEIBROCK.
